DOOR KNOB

Fred J. Russell, South Gate, Calif., assignor to Norris Industries, Inc., Los Angeles, Calif., a corporation of California

Substituted for abandoned design application Ser. No. 9,960, Dec. 28, 1967. This application Jan. 10, 1969, Ser. No. 15,300

Term of patent 14 years

Int. Cl. D8—03
U.S. Cl. 147—D8

FIG. 1.

FIG. 2.

FIG. 3.

FIG. 4.

FIG. 5.

FIG. 1 is a side elevational view of a door knob showing my new design.

FIG. 2 is a front elevational view.

FIG. 3 is a rear elevational view.

FIG. 4 is a longitudinal sectional view.

FIG. 5 is a cross-sectional view through the large portion of the knob.

The top view and the bottom view are identical to the side elevational view.

I claim:

The ornamental design for a door knob, as shown and described.
